UNITED STATES PATENT OFFICE

166,457

WINDING-KEY FOR A CLOCK OR SIMILAR ARTICLE

Henry Dreyfuss, Pasadena, Calif., assignor to The E. Ingraham Company, Bristol, Conn., a corporation of Connecticut

Application April 20, 1950, Serial No. 9,349

Term of patent 14 years

(Cl. D42—1)

To all whom it may concern:

Be it known that I, Henry Dreyfuss, a citizen of the United States, residing at Pasadena, in the county of Los Angeles and State of California, have invented a new, original, and ornamental Design for a Winding-Key for a Clock or Similar Article, of which the following is a specification, reference being had to the accompanying drawing, forming part thereof.

Fig. 1 is a perspective view of a winding-key for a clock or similar article, showing my new design;

Fig. 2 is a view thereof in side elevation;

Fig. 3 is an edge view thereof; and

Fig. 4 is a view looking toward the outer end thereof.

I claim:

The ornamental design for a winding-key for a clock or similar article, substantially as shown.

HENRY DREYFUSS.
